UNITED STATES PATENT OFFICE.

ERWIN LAVENS, OF NEW YORK, N. Y., ASSIGNOR TO THE GENERAL INCANDESCENT ARC LIGHT COMPANY, OF SAME PLACE.

ELECTRIC-ARC LAMP.

SPECIFICATION forming part of Letters Patent No. 555,706, dated March 3, 1896.

Application filed May 23, 1895. Serial No. 550,358. (No model.)

To all whom it may concern:

Be it known that I, ERWIN LAVENS, a citizen of the United States, residing at the city, county, and State of New York, have invented 5 Improvements in Electric - Arc Lamps, of which the following is a specification.

My invention relates to electric-arc lamps; and it consists of the mechanism employed for establishing and maintaining the light- 10 arc between the carbons.

The object of my invention is to simplify the construction of such lamps by decreasing the number of operative parts.

In the accompanying drawings, which will 15 serve to illustrate my invention, Figure 1 is a side view of a portion of a lamp embodying my invention. Fig. 2 is an end view at the right of Fig. 1. Fig. 3 is a plan view and partial section looking down with top plate removed. Figs. 4 and 5 are detail views of 20 the clutch mechanism, taken on the line $x-x$ of Fig. 2.

Similar letters of reference indicate like parts.

25 A is a base-plate; B, top plate; C and D, side plates. These plates are suitably secured together and serve to support the mechanism of the lamp.

E is a shunt-magnet, which is shown as 30 divided into two parts $E^1 E^2$, connected by means of a yoke F.

G is a shaft mounted on the adjustable pivots H H', located, respectively, in the side plates C and D. To the shaft is secured a 35 wheel or drum I, which is in operative engagement with carbon-support J. The carbon-support is, in the present instance, a rod-like support and is adapted to move lengthwise through and be guided by the 40 edges of the openings K in the plates A and B. I have shown the wheel I formed as a pinion and the carbon-support as a rod provided with a rack J' on its inner side.

I wish it understood that I do not limit myself to a rack-and-pinion engagement between 45 wheel I and carbon-support J, as I may use a flexible band or other connection, as more commonly employed in similar lamps, and which are well known to those skilled in the 50 use and manufacture of such lamps.

L is a clutch-wheel mounted on shaft G

and having its peripheral edge formed as a flange L'. It will be observed that as the wheel I and clutch-wheel L are fixedly mounted on shaft G the weight of the carbon-support J will, unless resisted, rotate the shaft and wheels to the right as it descends or to the left when elevated. Mounted on the pivots H H' is the armature M, which is formed of the side arms N O and head P. The arm N, Figs. 2 and 3, is carried upward, and when the armature drops bears against an adjustable screw-stop N', carried in an offset N² of the side plate, D. By adjusting the stop N' the distance which the head P of the armature will drop may be previously determined. 65

The arm O, Figs. 1 and 4, carries a dog or dogs Q, which in the present instance consist of a bar slotted transversely at its outer end to include the flange L' of the clutch-wheel L 70 and slotted longitudinally at its inner end to take over a pin R. Fastened at one end to the dog and at the opposite end to an extension O' of arm O is a helical spring. This spring, owing to the fact that the dog has a different 75 center of motion from that of the clutch-wheel, tends to cause the end of the dog to describe and arc which would cut the circle described by the periphery of the clutch-wheel. As a consequence the dog or dogs grip the outer 80 periphery of the clutch-wheel. The action of the spring or springs is manifestly aided by the weight of the carbon-support. An upward movement of the carbon-support, it will be seen, tends to slacken the bite of the dogs 85 and a free upward movement will be permitted.

The end P of the armature is arranged to 90 carry weights T, which may be adjusted for variations of electrical pressure.

From the foregoing description it will be observed that the armature M, considered as a whole, forms a lever of the first order. The carbon-support is carried on the short end of the lever and is overbalanced by the weights 95 of the long arm of the lever. Normally, therefore, the armature raises the carbon-support and separates the carbons, which is a requisite—*i. e.*, lamps of the type described.

U represents an arm pivoted at H and designed to be swung upon its fulcrum-point 100 and then secured in the adjusted position.

For this purpose I may provide a clamping-screw U' , secured to the arm U and moving in an arc-shaped slot U^2 on the side plate C . The free sides of the arm carry stops V V' , 5 projecting into the path of the dogs Q , and which serve when the dogs bear against them to push the outer end of the dogs backward to release the clutch-wheel L . Preferably, one of the stops V' is provided with an adjustable screw V^2 . By means of the arm U and screw V^2 the feeding movement of the carbon-support may be adjusted and determined.

The operation of the mechanism may be described as follows: When the current is turned on the magnet overcomes the weight of the armature, the shaft G is rotated to the right, the dogs Q strike the stops, the clutch-wheel is released and the carbon-support drops, and the arc carbons are brought into opposition. Immediately the armature drops and the carbon-support is raised to strike the arc. As the resistance of the arc increases the armature is gradually raised, and, as before, the carbon-support is lowered to compensate for consumption in the arc and to maintain the length of the arc.

I claim as my invention—

1. In an arc lamp, the combination of a movable carbon-support, a shaft carrying a wheel or drum from which the carbon-support is suspended, a clutch-wheel mounted on said shaft, a gravitally-acting armature which normally overcomes the weight of the carbon-support, a dog or dogs carried by said armature and moving with said clutch-wheel, an adjustable stop in the path of said dog or dogs, and a magnet for moving said armature, whereby said dog or dogs are brought 35 into engagement with said stop and thereby release the clutch when the length of the arc exceeds a predetermined limit, substantially as specified.

2. In an arc lamp, the combination of a movable carbon-support, a shaft carrying a wheel or drum from which the carbon-support is suspended, a clutch-wheel mounted on said shaft, a gravitally-acting armature which normally overcomes the weight of the carbon-support, a dog or dogs so pivoted as to move eccentrically to the axis of said armature, a magnet for moving said armature, and a stop against which the dog or dogs strike when the

armature in its movement reaches a predetermined point, thereby acting to release the carbon-support, and permit the upper carbon to feed, substantially as specified.

3. In an arc lamp, the combination of a movable carbon-support, a shaft carrying a wheel or drum from which said carbon-support is suspended, a clutch-wheel mounted on said shaft, a gravitally-acting armature which normally overcomes the weight of the carbon-support, said armature so pivoted as to have the same axis of rotation as the shaft on which the clutch-wheel is mounted, but arranged to move independently of said shaft, a dog or dogs pivoted upon said armature, and in such position that their pivotal points will, when the armature is actuated, move concentric to the armature-pivot, a magnet for moving said armature, and a stop in the path of said dog or dogs, whereby free upward movement of the carbon-support is permitted, a gradual downward movement of the carbon-support is effected to compensate for the consumption in the arc, and a quick downward movement when the length of the arc exceeds a predetermined limit.

4. In an arc lamp, the combination of a movable carbon-support, a shaft carrying a wheel or drum from which the carbon-support is suspended, a clutch-wheel mounted on said shaft, a gravitally-acting armature which normally overcomes the weight of the carbon-support, having the same axis of rotation as said shaft, but independent thereof, and a breaking device carried by, and moving with the armature which normally acts upon said clutch-wheel to prevent the downward movement of the carbon-support, but which permits free upward movement of said support, and a magnet for moving said armature and break device.

5. In an arc lamp, the combination of the movable carbon-support J , shaft G , wheel or drum I , clutch-wheel L , armature M , dog or dogs Q , and adjustable stop U , substantially as specified.

In testimony whereof I affix my signature in the presence of two witnesses.

ERWIN LAVIENS.
